(57) **CLAIM**

The ornamental design for a connector block, as shown and described.

DESCRIPTION

FIG. 1 is a bottom view of a connector block showing my new design;

FIG. 2 is a left side view thereof;

FIG. 3 is a right side view thereof;

FIG. 4 is a front view thereof;

FIG. 5 is a top view thereof;

FIG. 6 is a rear view thereof; and,

FIG. 7 is a perspective view thereof.

The broken lines in FIGS. 2-4 and 6 are included to illustrate unclaimed internal details and form no part of the claimed design.
